(57) **CLAIM**

The ornamental design for a candle warmer lamp, as shown and described.

DESCRIPTION

FIG. 1 is a front, right, and top perspective view of a candle warmer lamp, showing my new design;
FIG. 2 is a rear, left, and bottom perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof; and,
FIG. 9 is an enlarged view taken from the encircled portion labeled "9" in FIG. 1.
The dot dash broken lines denote the boundaries of the encircled portion in FIGS. 1 and 9 and form no part of the claimed design. The evenly spaced broken lines in the drawings depict the environmental structure that form no part of the claimed design.

1 Claim, 9 Drawing Sheets
